SAFETY RAZOR

Leonida Patrignani, Bologna, Italy

Application June 13, 1949, Serial No. 98,812

8 Claims. (Cl. 30—64)

1

The present invention relates to improvements in safety razors and more particularly to safety razors of the "Gillette" type.

Conventional safety razors have many disadvantageous features. For example, the conventional razor comprises a plurality of parts which together with a blade must be assembled for use and which must be taken apart after use in order to remove the used blade for cleaning or for replacement. Such cleaning involves washing and drying and sooner or later results in deterioration of the parts which are usually of brass plated with material such as silver, chromium or other suitable materials. The conventional razors are also relatively rigid and heavy so that the user can not so readily feel the degree of pressure of the blade on the skin.

An important object of the invention is to provide a novel and advantageous form of razor which will obviate the aforesaid and other disadvantages of the forms of safety razors heretofore in use.

Another object of the invention is to provide a safety razor which is very compact in form, economical to manufacture and efficient in operation.

Still another object of the invention is to provide a safety razor adapted to use single-edge blades formed by cutting or splitting a standard or conventional double edge blade.

Yet another object of the invention is to provide a safety razor in which all parts except the blade are formed from resilient wire which may be corrosion and oxidation resistant.

A further object of the invention is to provide a novel and advantageous form of razor which can be manufactured without requiring use of elaborate equipment such as usually required for machine and tool operation, and metal treatments in making a conventional safety razor.

According to a preferred embodiment of the invention, the razor may be made of non-corrosive resilient wire, preferably of non-oxidizable steel and of the order of 1.8 mm. in diameter. The wire in the handle is in the form of a helix with coils at the free end of slightly greater diameter to provide a head or knob. The free end of the wire in such larger coils is turned across the outer end of the last full coil at this end. At the inner end of the handle, the wire is formed into a smaller coil adapted to guide a double thickness of wire for a purpose to be stated hereinafter. From this smaller guiding coil or loop the wire extends in the same general direction as the axis of the handle to a point at a suitable distance from the handle. At this point the wire is formed into a generally rectangular frame and the free end of the wire is carried back along the wire supporting said frame and is held thereto by a coil therearound. Across said frame are

2

two blade supports on the outside of which the single edge blade rests with its back edge against one side of the frame.

The blade is held against said supports by a wire element or plunger having a straight portion extending across the outer side of a blade on the blade supports, the wire at the ends of said straight portion extending between said blade supports in position to pass through notches at the ends of the single edge blade, then inwardly from both sides to a central location and then side by side through said smaller guiding coil, and through said handle to its outer end where the two wire ends are hooked over the outer end of the wire of the handle. It will be evident that the plunger element is made up principally of a blade holding loop and a stem extending through said handle.

By compressing the coil of the handle, the blade holding end of the razor may be opened for insertion or removal of a blade.

The razor of the present invention has many advantages. From the standpoint of manufacture an advantageous feature is that the razor can be made entirely from one form of material namely resilient wire. There are two unitary main parts and two blade supporting members. The parts can easily be formed and permanently assembled. Furthermore there are no pivots to cause wear.

The razor of the present invention does not have to be assembled or taken apart, thus saving time, and is easy to use. The razor does not have to be dried after washing. The life of the razor of the present invention is substantially unlimited. The razor is elastic and light and works with a spring action that allows one to feel the degree of pressure on the skin. The shape and construction of the frame is such that the blade is held perfectly flat and is so exposed as to permit cleaning thereof without removal from the blade holding means. The blade is held accurately in position. The razor being very light and resilient is not likely to be injured if dropped and it is not likely to injure anything on which it is dropped.

Other objects, features and advantages will appear upon consideration of the following detailed description and of the drawings in which:

Fig. 1 is a top plan view of a razor embodying the present invention, in horizontal position;

Fig. 2 is a bottom plan view;

Fig. 3 is a view in elevation as seen from the left of Fig. 1;

Fig. 4 is a section taken along line 4—4 of Fig. 1;

Fig. 5 is a view illustrating the razor in use;

Fig. 6 is a view illustrating the manner of releasing and removing a blade from the razor; and

Fig. 7 is a view illustrating a conventional

double edge razor blade and the manner in which it may be cut to form two single-edge blades.

Referring to the drawings, the illustrated embodiment of the present invention comprises a handle 10 of resilient non-oxidizable wire in the form of a helix having near its outer end a knob 11 made up of coils of greater diameter than the others. At the outer end of said knob the free end 12 of the wire is turned across the last coil and is used in a manner to be brought out hereinafter. At the other end of said handle 10, the wire forms a smaller coil 13 of sufficient size to permit the sliding therethrough of a part 14 of another element, said part comprising two thicknesses of wire arranged side by side.

From said coil 13, the wire of said handle 10 comprises a straight portion 15 extending forwardly and inwardly toward the axis of the handle, and terminating at a point 16. Beyond the point 16, the wire is in the form of a generally rectangular frame 17 substantially perpendicular to portion 15 and comprising a half side 18, an end 19, a front side 20, another end 21 and a half side 22. At the inner end of said half side 22, a length 23 of the wire extends upwardly along portion 15 and has at its end a coil 24 tightly engag-

ing said portion 15.

As illustrated in Fig. 4, the half sides 18 and 22, are offset upwardly (Fig. 3) at points 25 and 26 respectively, for reasons to be set forth hereinafter. At the front of ends 19 and 21 are wire members or cross bars 29 and 30 parallel to side 20 of frame 17 and spaced apart slightly more than the diameter of the wire from which the razor structure is formed. The ends of these wire members 29 and 30 are pressed tightly around said ends 19 and 20.

The parts of said frame 17 and the members 29 and 30 are so arranged that if a flat single edge razor blade 31 (Figs. 3 and 6) is placed on said members 29 and 30 at the outer sides thereof with the sharp edge 32 extending toward side 20 of frame 17, the rear portion or edge of the blade will rest against the inner portions of said half sides 18 and 22, such inner portions being provided as by flattening with flat surfaces 27 and 28, respectively, for engaging the rear of said blade 31. Toward the cutting edge the blade has a shorter portion 33 (Fig. 6) providing forwardly facing shoulders 34 on the main body of the blade.

A blade 31 may be held in position against members 29 and 30 and with its rear against the central portions of half sides 18 and 22 by a part 36 of a wire element or plunger constituting an important part of the razor. Said part 36 is of such length as to extend across the blade portion 33 at the faces of said shoulders 34 and at the ends of said part 36 the wire turns back between parts 29 and 30 and just inside said ends 19 and 21. The turning back of the wire at the ends of part 36 provides short sections or arms 37 adapted to engage said shoulders 34. Said sections or arms 37 serve to guide the member 36 in its releasing and clamping movements. Inasmuch as a blade 31 is clamped against the fronts of members 29 and 30 with its rear against the flat surfaces 27 and 28 of half sides 18 and 22 the ends 19 and 21 must be offset rearwardly from the half sides 18 and 22 as by parts 18' and 22' bent downwardly and rearwardly from the ends of parts 18 and 22.

From the inner ends of arms 37, the two branches 38 extend to the central part of the head where they combine side by side in part 14 which extends rearwardly from the blade-hold-

ing head through the coil or loop 13 and through the handle 10 to the free end thereof where it takes the form of a hook 39 engaging the end 12 of the handle wire. Preferably the inner blade-engaging face of member or part 36 is flat to avoid bending a blade 31 gripped between parts 29 and 30 and member 36. Such flattening of part 36 also makes it wider and prevents it from being drawn through between parts or members 29 and 10 30 when no blade is interposed therebetween.

As illustrated in Fig. 6, a blade 31 in the razor may be removed by placing the forefinger 40 and the second finger 41 on opposite sides of parts 14 and 15 and in engagement with the inner end of the helical spring of the handle 10 and pressing the thumb 42 of the same hand against the outer end of the handle. As a result of this pressure the plunger element will be advanced with reference to the part carried by the handle and part 36 will be shifted away from the blade supports 29 and 30. The rear portion of the blade can then be engaged at its ends between the thumb and forefinger of the other hand and removed from the razor as indicated in dot-and-dash lines (Fig. 25 6) and arrow 43. Also a blade 31 may be inserted while the spring of the handle is suitably compressed.

If the handle 10 of the blade-holding razor be held vertical, compression of the spring will cause the blade to fall out of the razor. Insertion of a blade in the razor can also be effected very easily by holding the handle vertically with the blade-holding part up, compressing the spring, inserting the blade, and releasing the spring of the handle.

It is evident that the blade 31 is held firmly in place in the razor, rearward movement of the blade 31 being prevented by engagement at its rear with half sides 18 and 22 at the rear of frame 17 and forward movement by engagement of shoulders 34 with arms 37. The blade 31 is also held firmly against cross bars or blade supports 29 and 30 by part 36 of the plunger, due to the action of the strong compression spring of the handle 10. With this spring action there is no danger that the blade will become loose while in use, as may happen with other types of razors. The blade is held flat between part 36 and parts 29 and 30 which provide a three line contact, and is held against edgewise movement by two rear abutment surfaces 27 and 28, two front abutments provided by arms 37, and two side abutments also provided by arms 37.

Fig. 5 illustrates the use of a half blade 31 when mounted in the razor proper. Rod 20 of the frame 17 rests against the skin 43 and serves to steady and guide the razor blade 31.

The blade-carrying structure is so open that materials such as soap froth and cut hair are easily washed from the blade in the razor.

The blade 31 is held generally flat between straight members 29 and 30 and straight member 36 and due to the shoulders 34 is held against the abutments 34 due to engagement between the rear of the blade and portions of half sides 18 and 22. This arrangement makes it sure that the blades 31 will always project to the same extent.

The razor may also be used with single-edge blades 31a (Fig. 7) which may be produced by severing them from a standard or conventional double-edge blade 44 (Fig. 7) along median line 45-45. These blades would have rearward projections at their ends due to cutting the end connections, but these projections would be accommodated due to the shape of parts 18 and 22 of

frame 17. If desired such projections could easily be eliminated. Such severing of the blade 31a might be affected while the blade is in its paper wrapper.

An advantage of the blade and razor of the present invention is that the blade is narrow and the razor itself is very compact. Another advantage is that only one sharp edge at a time is subjected to the wear and tear of washing and wiping, whereas in a double-edge blade each edge is subjected to such wear and tear even if it is not used.

It should be understood that various changes may be made, and that certain features may be used without others, without departing from the true scope and spirit of the invention.

What is claimed is:

1. A razor for use with a single edge blade having a front cutting portion and front-facing shoulders at the ends thereof, comprising a frame with two parallel blade supports separated by a slot and means to abut from the rear a blade resting on said blade supports, blade-gripping means comprising a blade-gripping member to engage said blade opposite said slot and side members extending rearwardly through said slot and spaced to permit the insertion of said front cutting portion of said blade and to engage said shoulders, a handle supporting said frame, and a spring connection between said handle and said blade-gripping means to permit shifting thereof for insertion or removal of a blade.

2. The combination according to claim 1 wherein in the handle is a helical spring connected at its inner end to said frame and at its outer end to a stem passing through said helix and connected to said side members attached to the blade-gripping member.

3. The combination according to claim 1 wherein in said handle is a helix of resilient wire, said frame is formed of wire extending from one end of the coil, and said blade-gripping means comprises a single wire forming said blade-gripping member and arms, and extensions of said arms brought together in a stem extending through said helix and connected to the outer end thereof.

4. A razor comprising a handle of resilient wire in the form of a helix, a generally rectangular frame formed of the wire from one end of the helix and extending transversely with respect to the axis of the helix, parallel blade-supporting members extending across said frame and providing a slot therebetween; an element comprising a wire with a part extending parallel to said slot to engage the outer side of a blade over said slot and parts at the ends of said blade passing rearwardly through said slot and coming together in a stem extending through said helix to the far end thereof, and means connecting the outer ends of said stem and said helix.

5. A safety razor comprising a rod to engage one side of a blade, two rods at the opposite side of the blade with a slot therebetween opposite the first-mentioned rod, and a spring means to press

said rod at one side and the two opposite rods toward each other to hold said blade firmly in position.

5 6. The combination of claim 5 in combination with a handle connected at one end to said two rod supporting means and comprising a helical spring connected at the other end to said rod at the opposite side of the blade.

10 7. A razor for use with a single-edge blade having a front cutting portion and front-facing shoulders at the ends thereof, a helical wire spring terminated at one end by a transverse part constituting a holding pin extending across the outer end of the handle, the wire at the other end of said spring having a guiding loop of lesser diameter and beyond the guiding loop a generally rectangular frame having a rear side closed at its middle by the free end of the wire projecting from said guiding loop and providing an abutment for the rear edge of a blade, two parallel blade supports separated by a slot and secured at their ends to the front sides of the ends of said frame, and means for holding said blade on said blade supports with its rear engaging said abutment comprising a blade-gripping member on the opposite side of the blade from said slot and side members spaced to receive the front cutting-portion of said blade and engage said shoulders, and extensions of said side members brought together at the rear of said frame and passing through said handle and grasping said holding pin.

15 8. A razor comprising a handle of resilient wire in the form of a helix, a generally rectangular frame formed of the wire from one end of the helix and extending transversely with respect to the axis of the helix, parallel blade-supporting members extending across said frame and providing a slot therebetween; an element comprising a wire with a part extending parallel to said slot to engage the outer side of a blade over said slot and parts at the ends of said blade passing rearwardly through said slot and coming together in a stem extending through said helix to the far end thereof, the rear sides of said frame serving as an abutment for engagement by the rear edge of said blade and the front side of said frame being offset to one side of the blade position to serve as a guard for said blade.
